UNITED STATES PATENT OFFICE.

JOHN R. HAYS, OF BROOKLYN, NEW YORK

PRINTING-PRESS.

1,229,610.

Specification of Letters Patent. Patented June 12, 1917.

Application filed May 11, 1916. Serial No. 96,740.

To all whom it may concern:

Be it known that I, JOHN R. HAYS, a citizen of the United States, and a resident of the borough of Brooklyn, in the city of New York and State of New York, have invented certain new and useful Improvements in Printing-Presses, of which the following is a specification.

The invention relates to printing presses, and in many aspects thereof more especially to fast rotary newspaper presses and the like.

Objects and advantages of the invention will be set forth hereinafter in part and in part will be obvious herefrom, such objects being realized through the means and combinations pointed out in the accompanying claims.

The invention consists in the novel parts, constructions, arrangements, combinations and improvements herein shown and described.

The accompanying drawings, herein referred to and constituting a part hereof, illustrate one embodiment of the invention, and together with the description serve to explain the principles thereof.

Of the drawings:

Figure 1 is a top plan of a portion of a printing press illustrating an embodiment of the invention;

Fig. 2 is an end elevation looking at Figs. 1 and 3 from the left;

Fig. 3 is a side elevation looking at Fig. 1 from the bottom, and at Fig. 2 from the right;

Fig. 4 is a top plan exemplifying a somewhat different application of the invention; and

Fig. 5 is an elevation, partly in section, on the line A—B of Fig. 4.

Rotary printing presses such as are designed for fast newspaper work and like purposes, especially those of great product capacity, are built of relatively great width the form and impression cylinders, the inking rollers and other parts being of correspondingly great length, the press printing thus upon very wide webs. By having the press of very great width and with the form cylinders and impression cylinders of correspondingly great length, a product of a greater number of pages relatively to the speed of the press and to the revolutions of the cylinders and other parts is secured, but on the other hand, the speed of rotation

of the press cylinders and the inking rollers and associated parts is limited and diminished, due to their great length, which great length is necessitated by the great width of the press. If such long cylinders and inking rolls are rotated at high speed the result is streaky printing and uneven color, together with damage and impairment to the inking rolls and to the printing plates, due to centrifugal action, especially at and around the remotely supported central part of the long form and impression cylinders and of the inking rollers.

By the present invention the effective width of the press is maintained, the press is fed from a single wide web of customary width, but at the same time the form cylinders and impression cylinders, the inking rolls and associated parts are divided lengthwise into two parts and are provided with a central journal or bearing, without any waste of the central part of the web, and thereby a very much higher speed of rotation is safely attained despite the width of the press, and a much greater product is secured, which is likewise of better quality.

In the general arrangement of the press illustrated herewith as an exemplification of my invention, the press is shown printing upon a web four pages wide, the press cylinders being four plates long, that is of multiplate length. The form and impression cylinders are divided intermediately into two parts, and are provided with a central journal bearing, as are likewise the ink rollers and allied parts, while the entire width of the web is utilized as in the usual manner; or to the full extent as in the ordinary type of presses in which type the four plate long cylinders are unsupported throughout their length. The number of printing plates along the multiplate length form cylinder may be varied, as two plates, one at each side of the central bearing, may be employed, or a larger number may be employed so far as concerns many features of the invention.

Referring more particularly to the drawings, a form cylinder 1 is shown of multiplate length, and is divided into two parts 2 and 3 with a central journal or shaft 4, the cylinder having thus journal bearings 5 and 6 at either end thereof and another journal bearing 4 intermediately of its length, the two portions 2 and 3 of the cylinder being fixed to their common shaft 8

and rotating together. The press is provided, as embodied, with three upright frames 9, 10 and 11, extending longitudinally of the press. The two end journals 5 and 6 are supported on the frame members 9 and 11, and the intermediate journal 4 is supported on the frame member 10. In the illustrated embodiment, the form cylinder 1 is four plates long, that is, it has four plates 12, 13, 14 and 15, arranged along the cylinder and two or more plates around the cylinder. Longitudinally considered, two plates 12 and 13 are carried on the part 2 of cylinder 1, and the other two plates 14 and 15 are carried on the part 3 of cylinder 1. As stated, the plates may be arranged two or more on around, that is, circumferentially of cylinder 1, and the longitudinal arrangement preferably would be the same 20 in the case of each series considered longitudinally.

Coöperating with the form cylinder 1 is an impression cylinder 20, which impression cylinder is likewise in two parts 21 and 22, 25 corresponding to the two parts of the form or plate cylinder. Impression cylinder 20 has also an intermediate journal and a journal bearing 23 therefor in the central longitudinal frame member 10, and end bearings 30 18 and 19, respectively, in the frames 9 and 10, the two parts of the impression cylinder being fixed to their shaft 24, and rotating therewith. The cylinders 1 and 20 coöperate together as a printing couple to print 35 one side of the running web in a well-known manner.

Suitable inking mechanism for form cylinder 1 is provided, and in accordance with certain features of the invention, the form 40 inking rollers, and preferably the ink drum and associated rollers also, are divided internally and provided with a central journal bearing. The embodied form of inking mechanism is shown more or less conveniently and in a fragmentary manner. Form inking rollers 25 and 26 coöperate with the printing plates upon the form cylinder 1, the form inking rollers having journal bearings 27 and 28 at their two outer 45 ends and are journaled, respectively in the frame members 9 and 11, and also having a central journal bearing 30 journaled in the intermediate or central upright frame member 10. The form inking roller 26 is similarly constructed, and has the same reference numerals applied to its journal bearings. In the preferable form, the ink drum 31 is similarly constructed and is shown with a journal bearing 32 in the outer frame 11, 50 and a journal bearing 33 in the outer frame 9 and an intermediate journal bearing 34 in the intermediate frame 10.

The embodied form shows a perfecting press, and the second impression cylinder 35 65 is shown in two parts 36 and 37, with an

intermediate journal bearing 38, and end bearings 39, and is preferably of like construction with the impression cylinder 20 just described. The second form cylinder 40 is preferably the same in construction as the form cylinder 1, comprising two parts 41 and 42, with an intermediate journal bearing 43 in the frame member 10 and with end bearings 44 and 45 in the side frame members 9 and 11. Suitable driving gears 49 may be provided of convenient and approved form and arrangement. The web α runs through the two printing couples and is perfected thereby in a well known manner.

Means for supplying paper from a single roll to both parts of the printing couples are provided, and in the exemplified form thereof, the entire width of the web is utilized without waste. A web roll ω is arranged 80 longitudinally of the press, and preferably at one side thereof, and is supported in a suitable manner as by mandrel 50 carried in brackets 51 upon the press frame. From the roll the web α runs over a tension roller 52, having sliding bearings 53 mounted upon the machine frame, the bearings being acted upon by springs 54, this roll safeguarding the web from sudden strains tending to damage or disrupt it. The web then passes over 85 the smoothing roll 55 and from thence about a driven roll 56. The roll 56 is driven from the gear train 49 by intermeshing bevel gears 57.

Centrally of the web α as it passes over 100 the roll 56 is a rotary slitter 58, carried upon a shaft 59, which shaft is mounted in the cross frame members 60 and 61. The shaft 59 is driven by the gear and pinion 62 from the shaft of roll 56. The web α is thus slit 105 longitudinally and in the present case centrally of its web by the rotary slitter 58.

Each half or part of the slit web is then carried to alignment with one part of the printing couple at either side of the central bearing and run into the printing couple to be printed. As embodied, two turning bars are arranged, each in alignment to receive one part of the slit web, each turning bar also being in alignment with one part of the 110 printing couple and directing the corresponding part of the web thereinto.

As embodied, the left half of the web (referring to Fig. 1) passes over a turning bar 63, and is led into the lower side of the press 120 in Fig. 1, passing between the first plate cylinder and impression cylinder to be printed on one side, and thence between the second plate cylinder and impression cylinder, and is thereby perfected. The right-hand half of the web α , still referring to Fig. 1, after being slit as described, passes over a turning bar 64 and is led into the other side of the press, at the upper side in Fig. 1, passing between its part of the first 130

plate cylinder and its impression cylinder and between its part of the second plate cylinder and its impression cylinder, and being thereby perfected. It will thus be seen that 5 the entire width of the web is utilized as fully as in the usual arrangement, wherein the web roll is arranged transversely of the press, and wherein the various cylinders and the ink rollers are unsupported save at 10 their ends. By this arrangement the press may be run at very greatly increased speed over that of ordinary wide presses, and satisfactory and acceptable printing results are secured, which would be unattainable with 15 the old form of presses, and at the same time the inking rolls are preserved against injury and their inking action is maintained unimpaired. After the web is printed it may be brought together again for folding as may 20 be desired.

In Figs. 4 and 5 of the drawings is shown a double arrangement of a press constructed in accordance with the principles of the invention, showing a double ended press, with 25 two paper supply rolls, arranged longitudinally at either side of the press, one web roll supplying one of the presses and the other web roll supplying the other press. In this arrangement the web supply mechanism for 30 both presses occupies only the same floor space as a single web supply. The paper supply roll *y* is arranged longitudinally of the press at one side, and is readily and fully accessible, the web running in in a trans- 35 verse direction, and being longitudinally slit by the slitter 58, and passing over turning bars 63 and 64 in the manner previously described in connection with Figs. 1, 2 and 3. The other paper supply roll *z* is 40 similarly mounted at the opposite side of the press and is slit longitudinally by the slitter, and is run in transversely and directed to the printing couples of the other press, the turning bars therefor being arranged just 45 above or just below the turning bars for the other end of the press.

From all the foregoing it will be understood that a printing press has been provided realizing the objects and advantages herein 50 set forth, together with other objects and advantages. It will be also understood that changes may be made from the precise structure shown and described, within the scope of the accompanying claims, without departing from the principles of the invention, and without sacrificing its chief advantages. 55

What I claim as my invention and desire to secure by Letters Patent is:—

1. A rotary printing press including in 60 combination a printing couple comprising a form cylinder of multiplate length divided intermediately by a journal bearing and an impression cylinder of like construction, and a frame supporting the cylinder shafts at each end and at such intermediate bearing, a

full width paper supply roll, a slitter slitting the web longitudinally and means for directing one part of the slit web to one side of the printing couple and the other part of the web to the other side of the printing couple. 70

2. A rotary printing press including in combination a printing couple comprising a form cylinder of multiplate length divided intermediately by a journal bearing and an impression cylinder of like construction, a 75 frame supporting the cylinder shafts at each end and at such intermediate bearing, a full width paper roll arranged substantially lengthwise of the press and means for directing one part of the slit web to one side 80 of the printing couple and the other part of the web to the other side of the printing couple.

3. A rotary printing press including in combination a printing couple comprising a 85 form cylinder of multiplate length divided intermediately by a journal bearing and an impression cylinder of like construction, a frame supporting the cylinder shafts at each end and at such intermediate bearing, a full 90 width paper supply roll, a slitter slitting the web longitudinally and a turning bar directing one part of the slit web into one half of the printing couple and a turning bar 95 directing the other part of the slit web into the other part of the printing couple.

4. A rotary printing press including in combination a printing couple comprising a form cylinder of multiplate length divided intermediately by a journal bearing and an impression cylinder of like construction, a frame supporting the cylinder shafts at each end and at such intermediate bearing, a full width paper roll arranged substantially lengthwise of the press and a turning bar 100 directing one part of the slit web into one half of the printing couple and a turning bar 105 directing the other part of the slit web into the other part of the printing couple.

5. A rotary printing press including in 110 combination three upright parallel frame members extending lengthwise of the press, a printing couple comprising a form cylinder of multiplate circumference and length divided intermediately by a journal bearing 115 and an impression cylinder of like construction, said cylinders having the end bearings of their shafts supported in the outside upright frame members and their intermediate bearings supported in the central upright 120 frame member and driving gears for said cylinders located externally to the length of the cylinders.

6. A rotary printing press including in combination three upright parallel frame 125 members extending lengthwise of the press, a printing couple comprising a form cylinder of multiplate length divided intermediately by a journal bearing and an impression cylinder of like construction, said cylinder 130

ders having the end bearings of their shafts supported in the outside upright frame member and their intermediate bearings supported in the central upright frame member, 5 means for longitudinally slitting a web supply and directing one portion thereof to the printing couple at one side the central frame member and the other portion to the printing couple at the other side of the central 10 frame member.

7. A rotary printing press including in combination three upright parallel frame members extending lengthwise of the press, a printing couple comprising a form cylinder of multiplate length divided intermediately by a journal bearing and an impression cylinder of like construction, said cylinders having the end bearings of their shafts supported in the outside upright frame 15 members and their intermediate bearings supported in the central upright frame member, a paper roll supported at the side of the press and arranged longitudinally thereof, a slitter slitting the web longitudinally, and 20 means for directing one part of the slit web into one side of the printing couple and for directing the other part of said web into the other side of said printing couple.

8. A rotary printing press including in combination three upright parallel frame members extending lengthwise of the press, a printing couple comprising a form cylinder of multiplate length divided intermediately by a journal bearing and an impression cylinder of like construction, said cylinders having the end bearings of their shafts supported in the outside upright frame members and their intermediate bearings supported in the central upright 30 frame member, a paper roll supported at the side of the press and arranged longitudinally thereof, a slitter slitting the web longitudinally, a turning bar for directing one part of the slit web into one side of the 35 printing couple and a turning bar for directing the other part of said web into the other side of said printing couple.

9. A rotary printing press including in combination three parallel upright frame 50 members extending longitudinally of the press, a transverse shaft having end bearings in the outside upright frames and an intermediate bearing in the middle upright frame, a two part form cylinder, one part thereof 55 between one outside frame and the middle frame, the other part of said cylinder between the other outside frame and the middle frame, both parts of said form cylinder fixed to said shaft and rotating together, and 60 an impression cylinder therefor of like construction, a paper supply roll disposed longitudinally of the press, a longitudinal slitter, a turning bar located centrally of one part of the press and directing a part of the slit 65 web thereto, and a turning bar located cen-

trally of the other part of the press and directing the other part of the slit web thereto.

10. A rotary printing press including in combination three parallel upright frame members extending longitudinally of the 70 press, a transverse shaft having end bearings in the outside upright frames and an intermediate bearing in the middle upright frame, a two part form cylinder, one part thereof between one outside frame and the 75 middle frame, the other part of said cylinder between the other outside frame and the middle frame, both parts of said form cylinder fixed to said shaft and rotating together, and an impression cylinder therefor of like 80 construction, a paper supply roll, a longitudinal slitter, and means for directing one part of the slit web to one part of the press and the other part of the slit web to the other part of the press.

11. A printing press including in combination two press members arranged longitudinally of each other, each press member comprising a printing couple having a form cylinder of multiplate length divided intermediately by journal bearings and an impression cylinder of like construction, the press frame comprising three upright substantially parallel members, the central frame member providing journal bearings for the 95 intermediate journals of the cylinders of the printing couple, a plurality of paper supply rolls arranged centrally and longitudinally relatively to the press members, and side by side, means for slitting each web longitudinally and means for directing the slit web parts into the printing couples of the respective press members.

12. A printing press including in combination two press members arranged longitudinally of each other, each press member comprising a printing couple having a form cylinder of multiplate length divided intermediately by journal bearings and an impression cylinder of like construction, the 105 press frame comprising three upright substantially parallel members, the central frame member providing journal bearings for the intermediate journals of the cylinders of the printing couple, a plurality of 110 paper supply rolls arranged centrally and longitudinally relatively to the press members, and side by side, means for slitting each web longitudinally and means comprising sets of superimposed angle bars for directing the 115 slit web parts into the printing couples of the respective press members.

13. A rotary printing press including in combination three parallel upright frame members extending longitudinally of the 125 press, a transverse shaft having end bearings in the outside upright frames and an intermediate bearing in the middle upright frame, a two part form cylinder, one part thereof between one outside frame and the middle 130

frame, the other part of said cylinder between the other outside frame and the middle frame, both parts of said form cylinder fixed to said shaft and rotating together, an
5 impression cylinder therefor, means for longitudinally slitting a web and directing one part thereof to the form cylinder at one side of the frame and the other part thereof to the form cylinder at the other side of the frame.

10 14. A rotary printing press including in combination a printing couple comprising a centrally supported cylinder, a wide web

supply, means for longitudinally slitting the web and directing one part thereof into the printing couple on one side said central support and directing the other part to the other side of said support.

15 In testimony whereof, I have signed my name to this specification, in the presence of 20 two subscribing witnesses.

JOHN R. HAYS.
